UNITED STATES PATENT OFFICE.

HAROLD I. KOPPELMAN, OF CHICAGO, ILLINOIS, ASSIGNOR TO U. S. SANITARY SPECIALTIES CORPORATION, OF CHICAGO, ILLINOIS, A CORPORATION OF ILLINOIS.

DISPENSING VALVE.

Application filed May 7, 1923. Serial No. 637,072.

To all whom it may concern:

Be it known that I, HAROLD I. KOPPELMAN, a citizen of the United States, residing at Chicago, in the county of Cook and State 5 of Illinois, have invented certain new and useful Improvements in Dispensing Valves, of which the following is a specification.

This invention relates to liquid dispensing apparatus and pertains particularly to toilet 10 devices designed for dispensing liquid soap in washrooms.

Heretofore it has been customary to dispense liquid soap from individual containers or from a pipe line supplying a plurality of 15 dispensing devices associated with different wash basins, which line is fed from a tank or reservoir usually located on the wall of the room in which the apparatus is installed. It is now proposed to provide a complete 20 system for supplying a considerable number of separate washrooms or lavatories situated on different floors of large buildings, such as office buildings and hotels, the entire 25 system being fed from a single large supply reservoir located at the top of the building.

In the use of apparatus for dispensing liquid 30 soap difficulty has been experienced heretofore in avoiding leaking or clogging of the dispensing valves, it having been the experience that certain constructions which 35 operate on sufficiently small clearances to afford leak-proof construction were subject to clogging from gummy deposits out of the soap, or from products of reactions occurring

40 between the soap mixture and the metal or other material of which the dispensing devices were made. Because of the constant and rather violent usage to which the dispensing devices are subjected they are subject to wear which tends to make them 45 leaky, an undesirable condition which is further augmented, in pipe line systems, by the hydrostatic pressure under which the material is fed to the dispensing devices from

50 the supply tank on the wall. It will be obvious, therefore, that the tremendous increase in this hydrostatic pressure which will result from placing the supply reservoir near the top of a tall building, and piping the material therefrom to lavatories on the different floors, would subject the dispensing valves to such pressures as will tend to increase by many fold the possibilities and

probabilities of leakage through the dispensing valves.

The general purpose of the present invention is the provision of a valve construction designed primarily to meet the requirements imposed by conditions such as those enumerated above but which, of course, is not 55 limited in its utility or intended use to employment in extensive systems. More particularly, a purpose of the invention is the provision of a dispensing valve which will operate easily to discharge a uniform quantity of liquid at each operation, which will not be subject to clogging by deposits or by foreign matter which may be introduced with the liquid, and which will remain leak-proof incident to hard usage or under high 60 pressure of the dispensed liquid.

A more specific purpose of the invention is the provision of a dispensing device in which the operating parts are quickly and readily accessible for purposes of inspection, cleaning or repair, without requiring 65 associated devices being put out of operation.

Another object is the provision of such a device wherein the portions which close the 70 outlet are relieved from the hydrostatic pressure maintained upon the liquid to be dispensed.

A further object is the provision of a device of the sort described which is substantially fool-proof, in that it cannot be disabled by petty tampering after it is installed.

A further object is the provision of a device of the sort specified which is positive 75 in operation so as to insure the discharge or dispensing of an intended quantity of liquid at each operation.

Other and further objects of the invention will be pointed out hereinafter, indicated in 80 the appended claims or obvious upon an understanding of the present disclosure.

For the purpose of the present application I have shown in the accompanying drawing forming a part of this specification, one form in which the invention may be embodied, but it is to be understood that the same is here submitted for illustrative purpose only, and that it is not to be accorded any interpretation such as would 85 have the effect of limiting what I purport

to secure by Letters Patent, short of the true and most comprehensive scope of the invention.

In said drawing,

5 Fig. 1 is a longitudinal sectional elevation of the device showing the operating parts in normal position;

10 Fig. 2 is a similar view showing the position of the parts at the end of the operation by which the liquid is dispensed or ejected;

15 Fig. 3 is a similar view showing the position of the parts at a time during the return to normal position, when the device is being supplied with a new charge for subsequent ejection;

20 Fig. 4 is a detail in the nature of a longitudinal section of a portion of the piston or plunger;

25 Fig. 5 is a section taken on substantially line 5—5 of Fig. 4, but on an enlarged scale; and

Fig. 6 is a section taken substantially on the line 6—6 of Fig. 1.

30 The nature of the invention will be most readily understood by reference to this illustrative embodiment in detail. By reference to the drawing, let it be understood that the numeral 1 designates a pipe constituting a portion of a supply line leading from a reservoir containing the liquid to be dispensed, and the numeral 2 designates a suitable connection to said pipe in the nature of an elbow or T affording a mounting for the dispensing device. The dispensing device includes a casing portion which, for purposes of convenience in manufacture and assembling, may be made in two parts, designated 4 and 5, and which I will term 35 respectively the valve bushing and barrel. These parts are joined in suitable fashion, as by the screw joint 6, so that they may be mounted together upon the member 2. The valve bushing includes a longitudinal bore 7 which I will call a valve chamber, and which communicates with a bore 8 of smaller section, which I will call the inlet port. The latter communicates with the bore of the barrel 5, forming a passage 40 whereby liquid may flow from the valve chamber 7 into the barrel. At a suitable distance in front of the inlet port 8, the barrel is provided with a laterally opening outlet port 9. The front or outer end of the barrel 5 is closed by a stem 10 mounted for 45 longitudinal reciprocation through a packing gland 11, the barrel being provided with an internal flange 12 against which the packing is seated, and which forms a stop 50 arranged for engagement with a flange 14 on the stem to limit outward movement of the latter. On its outer end the stem 10 carries a button or head 15 whereby it may be manipulated by hand, and which forms 55 a stop limiting the inward movement of the

stem. At its inner end the stem is bored to afford an axial socket 16 adapted to receive the shank 17^a (see Fig. 4) of the plunger 17. The plunger is provided with an annular flange 18 against which a flexible cup washer 19 and an expansible spring washer 20 are clamped by a nut 21 which is screw seated on the shaft of the plunger. The plunger shaft is provided with an axial bore 22 which opens laterally through the ports 24. Mounted for telescopic movement in the bore 22 is a valve stem 25, the diameter of which, however, is substantially less than the diameter of the bore 22, so that ample space is afforded about the stem for passage of liquid into the bore. An extension coil spring 26, which preferably is secured at one end to the valve stem and at the other to the shaft of the plunger, is effective to support the former upon the latter in substantially the relationship illustrated in Fig. 4, when the spring is normal. Adjacent its rearward extremity the valve stem 25 carries a valve 27, which I will designate the confining valve, beyond which the valve stem continues as an extension 28. The plunger return spring 29 encompasses the valve stem 25 and the spring 26, and is seated at its rearward end against the valve bushing 4 and at its forward end against the nut 21, under compression, so that it is effective to retain the shank 17^a of the plunger seated in the socket 16 of the stem, and the stem in its outer position with the flange 14 seated against the stop flange 12. In such position, it will be observed, the outlet port 9 is covered by the cup washer 19 and effectively closed against egress of material therethrough from the bore of the barrel. The fit between the shank 17^a of the plunger and the socket 16 of the stem is preferably such that the stem may be rotated without rotating the plunger, the latter being held in position by the frictional engagement of the cup washer against the wall of the barrel, under the yielding pressure of the spring washer 20. With the parts in this position the extension 28 projects into the inlet port 8, there being a sufficient clearance between the surfaces of said parts to permit the ready flow of liquid through the port. With the plunger in this forward position, moreover, the confining valve 27 is spaced apart from the valve bushing and the inlet port.

10 In the valve chamber 7 is housed the inlet valve 30 having a shank portion of such size and form that liquid may flow past it to the outlet port 8, and a conical nose portion adapted to seat at the rearward end of the inlet port in such fashion as to effectively close the same and prevent passage of liquid from the valve chamber thereto. The inlet valve 30 is normally retained in seated position by its spring 31 which is confined 11

- at its rearward end by a bushing 32 which has an aperture 34 through which liquid may enter the valve chamber from the connection 2. The relationship of the inlet 5 valve 30 to the confining valve 27 and the extension 28 is such that the inlet valve may be unseated by pressure from the extension 28 upon rearward or inward movement of the plunger, as illustrated in Figs. 2 and 3; 10 while upon such inward movement of the plunger to a certain extent, but not to its full extent, the confining valve 27 will seat at the inner end of the inlet port 8 and effectively close the same against passage of 15 liquid from the barrel thereinto.
- I will now describe the operation of the device. Let it be assumed that the pipe connections 1 and 2 are supplied with liquid to be dispensed, which is maintained under 20 hydrostatic pressure, and that there is a quantity of such liquid in the bore of the barrel 5, placed there by a preceding operation of the device. The parts occupy the 25 positions illustrated in Fig. 1. The operator places the base of the palm of the hand against the button 15 with the fingers extending below the outlet port 9, and pushes inwardly, compressing the spring 29. Before the washer 19 uncovers the port 9, the 30 confining valve 27 closes the port 8, thereby confining a charge of material in the bore of the barrel. A further inward movement of the plunger compresses the valve spring 26, relative movement of the plunger and valve 35 27 being accommodated by the telescopic connection of said parts. Incident to such further inward movement of the plunger, the liquid is displaced from the bore of the barrel, through the channels 22 and 24, and 40 out the port 9, which, of course, is uncovered during the ejecting portion of the plunger movement. Meanwhile the inlet valve 30, prior to the seating of the confining valve 27, has been unseated and moved to the position illustrated in Fig. 2, which 45 figure illustrates the positions of the parts at substantially the end of the inward or ejecting movement of the plunger. The head 15 then being released by the operator, the plunger return spring 29 will become effective to move the plunger outwardly, first 50 closing the outlet port 9, and then unseating the confining valve 27 while the inlet valve 30 is held unseated by the extension 28. During a portion of the outward movement 55 of the plunger, therefore the barrel bore will be in communication with the valve chamber 7 by way of the inlet port 8, while the outlet port 9 will be closed by the cup washer 19, the parts occupying positions approximate to those illustrated in Fig. 3. During the return movement of the plunger 60 with the parts in this relationship, viz, with the outlet port closed and the inlet port open, a charge of liquid will enter the bore of the barrel through the inlet port from the valve chamber 7, impelled by the hydrostatic pressure. Further outward movement of the plunger will permit the inlet valve 30 to seat, thereby effectively cutting off the 70 portions within the barrel from the hydrostatic pressure of the liquid in the valve chamber.
- In the event it becomes desirable to inspect the operating parts of the device, the barrel 5 may be unscrewed from the bushing 4 and completely removed therefrom together with the parts which it houses. The inlet valve 30 prevents any escape of liquid upon such removal of the barrel, and after such removal, the entire plunger assembly may be removed from the barrel by simply withdrawing it through the rearward opening, as permitted by the loose mounting of the shank portion 17^a in the socket of the stem. 75
- A device of this construction operates easily and uniformly to dispense a measured charge upon the inward movement of the plunger while the hand of the operator is below the outlet port. It is free from leakage, because the outlet is effectively closed to prevent egress of the small charge retained in the barrel and the parts are free from the hydrostatic pressure in the supply lines. The operating parts are not subject 80 to clogging because the liquid is afforded free passage in the dispensing operation and there is no tendency to force it into crevices between moving parts. 85
- I claim:
1. In a liquid dispensing system, the combination with a supply line, of a dispensing device having an inlet port and an outlet port, a valve normally closing the inlet port against pressure from the supply line, means normally closing the outlet port, and an operating member movable to open said valve while the outlet port is closed, to admit liquid from the supply line, said operating member being operable to open the outlet port and to eject liquid therethrough. 90
  2. A liquid dispensing device comprising a casing having an inlet port and an outlet port, a plunger operable in said casing to eject liquid through the outlet port, means operable by the plunger for closing the outlet port when the plunger is in normal position, a valve closing the inlet port when the plunger is in normal position, a confining valve for closing the inlet port to prevent egress of liquid from the casing therethrough, and means operable by the plunger for opening and closing said valves while the outlet port is closed. 95
  3. In a dispensing device, the combination of a casing having an inlet port and an outlet port, a plunger operable in the casing to eject liquid through the outlet port, an inlet valve normally closing the inlet port, an outlet valve controlling the outlet port, said 100

valves being movable independently and means operable by the plunger to open the inlet valve while the outlet valve is closed.

4. A liquid dispensing device comprising a casing having an inlet port and an outlet port, a plunger operable therein to eject liquid through the outlet port, an outlet valve operable by the plunger and arranged to close the outlet port during part of the 10 ejecting movement of the plunger, a confining valve operable by the plunger to close the inlet port, an inlet valve normally closing the inlet port, and means operable by the plunger for retaining the inlet valve in 15 open position during part of the return movement of the plunger.

5. A dispensing device comprising, in combination, a valve bushing arranged for attachment to a supply line, a barrel member demountably connected to the bushing and having communication therewith through an inlet port, an inlet valve in the bushing normally closing said inlet port, means whereby the inlet valve is maintained 20 in normal position when the barrel is dismounted from the bushing, a valve in the barrel for closing the inlet port, a plunger operable in the barrel to eject liquid therefrom, and means; including the valve last 25 mentioned, operable by the plunger for controlling the inlet valve.

6. A dispensing device comprising the combination of a valve bushing adapted for connection to a supply line, said bushing being provided with a channel for the passage 30 of liquid therethrough, a valve in the bushing normally closing said channel, a barrel

connected to the bushing for reception of liquid from said channel, and demountable therefrom while said valve is in normal position, a plunger operable in said barrel and cooperating with the walls thereof to eject liquid therefrom, and yielding means operable by said plunger for unseating said valve to admit liquid to the barrel. 40 45

7. In a dispensing device, the combination of a casing having an inlet port and an outlet port, a stem mounted for reciprocatory movement through one end of the casing, a plunger operable in said casing by said stem 50 for ejecting liquid through the outlet port, a valve normally closing the inlet port, said valve being operable by said plunger to admit liquid through the inlet port, and a spring for actuating said plunger and stem, 55 said plunger being removable from the casing independently of the valve and stem.

8. A dispensing device adapted for connection to a supply line and comprising a casing having an inlet port and an outlet 60 port, a plunger operable in the casing to eject liquid through the outlet port, an inlet valve normally closing the inlet port to prevent passage of liquid therethrough from the supply line, a confining valve for closing 65 the inlet port to prevent passage of liquid therethrough from the casing, an outlet valve controlling the outlet port, and means operable by the plunger to hold each of said valves in open position. 70

In testimony whereof I have hereunto signed my name.

HAROLD I. KOPPELMAN.
